UNITED STATES PATENT OFFICE.

WILLIAM A. BLOOD, OF CLEVELAND, OHIO.

FILING-BOX.

1,244,694.

Specification of Letters Patent. Patented Oct. 30, 1917.

Application filed August 18, 1916. Serial No. 115,686.

To all whom it may concern:

Be it known that I, WILLIAM A. BLOOD, a citizen of the United States, residing at Cleveland, in the county of Cuyahoga and 5 State of Ohio, have invented certain new and useful Improvements in Filing-Boxes, of which the following is a specification.

This invention relates to filing boxes and is particularly adaptable to the now common 10 accepted card system of keeping accounts and also indexes.

The main object of this invention resides in the provision of a filing box wherein the base portion is so constructed that the pack 15 of cards contained therein may be arranged and held in such manner that each one is at a slightly higher level than the succeeding one, whereby it is possible to easily take hold of the first card to cause its removal. 20 In this connection, my invention also resides in so constructing the base portion as to particularly adapt it to sliding drawer type of filing cabinets, although I do not specifically limit myself to the definite meaning of "drawer", since obviously the structure might be modified and still be within 25 the spirit of the invention.

A further object of the invention resides in the combination of a set of cards, each 30 having a notch along its lower edge, with a file box provided with a rib in its base and which file box is wider than the cards by at least equal to the distance of the notches from one edge of the cards. By this arrangement, after one of the cards has been 35 used, it may be shifted laterally to indicate that it has been in use and still keep its correct position in the file.

The preferred embodiment of my invention 40 is shown in the accompanying sheets of drawings, in which similar characters of reference designate corresponding parts, and in which:

Figure 1 is a view in perspective showing 45 my improved type of file box,

Fig. 2 is a longitudinal vertical section of the structure as shown in Fig. 1,

Fig. 3 is a longitudinal vertical section taken through the file box, but showing the 50 base in its collapsed position,

Fig. 4 is a transverse section as represented by line 4—4 of Fig. 2, and,

Fig. 5 is a section showing particularly 55 the arrangement of notched cards with the ribbed base.

In these several views, the cabinet is represented as being a drawer or box 1, having a rear end 2, and a front end 3 hinged to a rigid or stationary base 4, as is shown at 5. This front end is hingedly mounted for purposes to be presently described and may be temporarily held in any position of adjustment by means of the arcuate spring latch members 6 notched on their undersides as shown at 7, which notches are designed to 60 coöperate with outwardly extending pins 8 carried by the sides of the file box itself. This box is also provided with a supplemental base formed of a plurality of sections 9, 10 and 11, the section 9 being the rear 65 section and being pivotally anchored as is shown at 12 to the rear corner of the box 1. The intermediate section 10 is hingedly connected on its opposite ends to the front and rear sections, as is shown at 13 and 14 respectively, and the sections 9 and 10 are of 70 such length that when they are in the position shown in Fig. 3, they occupy approximately the entire length of the box 1. The section 11 is free at its upper end and like- 75 wise the pivotal connections 13 and 14 are entirely independent of connection with the box 1. The front section 11 is of approximately the same height as the front end 3 of the box and when the sections are moved 80 to the position shown in Fig. 2, the upper end of the front base section 11 is designed to coöperate with serrations 15 carried by the inside of the pivoted front end 3, as is shown. The box 1 is also provided with a 85 pair of longitudinally extending slide rods 16, upon which the follow block 17 is slidably mounted and which frictionally engages these slide rods 16. This follow block is centrally cut out, as is shown at 18, in 90 order that it may be moved back and forth when the base sections have been made to assume an inclined position. Also, the base sections 9 and 10 are provided adjacent one 95 edge with a rib shown at 19 and this rib is designed to coact with notches 20 carried by each of the filing or account cards 21. Reference to Fig. 4, will show that the box 1 is of a greater width than the cards 21 and this additional width must at least equal 100 the distance the notches 20 are from the edges 22 of the cards 21, so that the same may be shifted laterally when desired.

The manner of using my file is as follows: 105 The cards are normally placed in the rear 110

portion of the box and when the same is in use, the base sections are made to assume the inclined positions shown in Fig. 2, whereupon the front card will always be at 5 a slightly higher level than the next succeeding rear card, thus rendering it easy to remove the cards one at a time. The serrations 15 coact with the front end of the base section 11 to hold the various base sections 10 in their inclined positions and if desired, the front hinged end 3 may be swung to the dotted line position shown in Fig. 2. This hinging of the front end is to add to the ease or convenience of the operator or 15 user. After a card has been removed and posted, it may be placed in the position occupied by the cards upon the base sections to the left of Fig. 2 and as each card is posted, it may be shifted laterally to bring 20 its notch 20 into engagement with the rib 19. Inasmuch as it is unlikely that each card will be used each time, this manner may be adopted to indicate the active accounts for that day. After the posting operation has 25 been completed, the base sections may again be moved about their pivot connections to assume the positions shown in Fig. 3, whereupon the cards may again be moved back to the rear end of the cabinet and be in position 30 for a similar operation the succeeding day.

Thus, it will be apparent that I have provided a cabinet which will add considerably to the convenience of the user and wherein 35 considerable time may be saved in the keeping of accounts by the card system.

What I claim, is:

1. A filing box comprising a drawer member, and a base for said drawer formed of 40 sections hingedly connected together normally lying flat within the bottom thereof and normally upstanding end piece located adjacent one end of said drawer hingedly connected to one of said sections and forming 45 a portion of said base, said sections being arranged to be moved to such position within the drawer that inclined surfaces are presented.

2. A filing box comprising a drawer member, a base for said drawer formed of sections 50 hingedly connected together, one end of said base being pivotally anchored to said member and the other slidable thereover whereby inclined surfaces are pre-

sented, and means whereby the sections may be temporarily held in such inclined position.

3. A filing box comprising a drawer member, a base for said drawer formed of a front, rear and intermediate section, the intermediate section being hingedly connected 60 at its opposite ends to said front and rear sections respectively, one of the other sections being pivotally anchored at its free end to said drawer member, the other end of the base being slidable within the drawer 65 whereby inclined surfaces are presented, and means whereby the sections may be temporarily held in such inclined position.

4. A filing box comprising a drawer member, a base for said drawer formed of a front, rear and intermediate section, the intermediate and rear sections approximately 70 equaling the length of said drawer and the front section being normally upright against the front of the drawer, the intermediate 75 section being hingedly connected at its opposite ends to the front and rear sections respectively, the rear section being pivotally anchored to the drawer at its rear end, the other end of the base being slidable within 80 the drawer whereby inclined surfaces may be presented, and means whereby the sections may be temporarily held in such position.

5. A filing box comprising a drawer member 85 including a hinged front, a base for said drawer formed of a front, rear and intermediate section, the intermediate and rear sections approximately equaling the length of said drawer and the front section being 90 normally upright against the front of the drawer, the intermediate section being hingedly connected at its opposite ends to the front and rear sections respectively, the rear section being pivotally anchored to the 95 drawer at its rear end, the other end of the base being slidable within the drawer whereby inclined surfaces may be presented, means whereby the sections may be temporarily held in such position, and means for temporarily holding said front in a lowered position.

In testimony whereof I affix my signature in presence of two witnesses.

WILLIAM A. BLOOD.
